UNITED STATES PATENT OFFICE.

GUSTAV B. SCHOU, OF NEW YORK, N. Y., ASSIGNOR OF ONE-HALF TO SAMUEL GOLDBERGER, OF NEW YORK, N. Y.

SANDING DEVICE FOR TRACTION WHEELS.

Application filed March 7, 1922. Serial No. 541,725.

To all whom it may concern:

Be it known that I, GUSTAV B. SCHOU, a citizen of the United States, residing at the city of New York, borough of Manhattan, in the county of New York and State of New York, have invented certain new and useful Improvements in Sanding Devices for Traction Wheels, of which the following is a specification.

10 This invention relates to traction vehicles such as automobiles, railway cars, or other motor operated vehicles in which the operation or propulsion is dependent upon friction or traction between the driving wheels and the track or roadway.

15 Among the objects of the invention therefore is to provide means carried by the vehicle and at all times under convenient and reliable control by the motorman or driver whereby a friction medium such as sand may be distributed upon or applied to the roadway or track for engagement by the traction wheels so that not only may the wheels be given the necessary friction for 20 the purpose of propulsion of the vehicle, but also, especially in connection with automobiles, to provide such safeguards as will prevent the dangerous and oftentimes disastrous skidding of the vehicles.

25 Another object of the invention is to provide a means for applying or distributing sand or the like to the roadway which includes a charge of sand supplied in the receptacle which may be applied to or removed from the vehicle at will, and wherein the sand may be supplied and retained for an indefinite length of time in such perfectly dry condition as to be sure to flow freely from the receptacle to the point of 30 application desired. To this end the charge of sand or the like is supplied in a form of a cartridge comprising an air and water tight shell or container of either a cheap discardable nature or one which may be of 35 a more substantial structure and refillable, but in all cases from which the sand will be delivered under the control of the operator or as conditions may require as a result of 40 the opening of the shell either by the provision of a movable part thereof or by the 45 rupture of a portion of the shell structure.

50 Another object of the invention is to provide a plurality of sand cartridges arranged preferably in a series so as to present the

cartridges singly and in succession into 55 position for the delivery of the contents as desired.

With the foregoing and other objects in view the invention consists in the arrangement and combination of parts hereinafter 60 described and claimed, and while the invention is not restricted to the exact details of construction disclosed or suggested herein, still for the purpose of illustrating a practical embodiment thereof reference is had 65 to the accompanying drawings, in which like reference characters designate the same parts in the several views, and in which—

Figure 1 is a vertical sectional view of 70 a sanding apparatus embodying my invention.

Fig. 2 is a vertical section at right angles to Fig. 1.

Fig. 3 is a bottom perspective of one of 75 the cartridges indicating one means of providing for the discharge of its contents.

Fig. 4 is a face view of one of the check members.

Fig. 5 is a sectional detail on the line 80 5—5 of Fig. 1.

Fig. 6 is a perspective view of the wire opener.

Referring now more specifically to the drawings as a practical embodiment of the 85 invention, but without unnecessary limitation to the specific mechanism illustrated, I indicate at 10 a supporting member such as the running board of an automobile or a portion of a car frame or body located just 90 in advance of a traction wheel 11 whose mud-guard is indicated at 12. 13 indicates a casing of any suitable structure, but preferably of such a nature as to possess the requisite strength for protection of the 95 traction medium to be delivered therefrom. Said casing includes a door or lid 14 shown as accessible at the side of the running board and which when opened or removed will give free access to the entire interior 100 of the casing. The casing as shown is in the nature of a cylindrical drum, in the center of which is journaled a carrier comprising a shaft 15, the main support for the shaft being a bearing 16 constituting a 105 fixed part of the end wall of the casing. On the door however is a central cone bearing 17 which in co-operation with the end of

the shaft serves as a centering device and auxiliary support therefor when the door is shut.

As above premised one of the principal features of this invention is the friction medium unit indicated as in the nature of a segmental cartridge 18 which may be of cheap paper or the like and discardable after being once used, or may be of a more substantial or permanent nature but provided along one side with a cheap frangible panel 19 of any suitable form to meet the requirements. If desired the advancing edge portion of the panel may be provided with a pull member 20 such as a wire whereby to insure the complete and effective rupture of the panel and the full opening of the delivery mouth 21 of the cartridge. I show an endless series comprising eight of these cartridges adapted to be brought into delivery position in succession. Obviously, however, any other number might be employed and the cartridges might be arranged in any other desired manner for successive delivery.

The means indicated for supporting and controlling the cartridges comprises radial walls 22 fitted upon the shaft 15 within the casing 13, each wall being provided with two flanges 23. The flanges are so designed as to embrace or engage over the edge portions of the cartridges to hold the same steady and from movement with respect to the casing. The portion of each cartridge that is not embraced by the walls and flanges is the portion farthest from the axis of the shaft 15, and hence is the portion that sweeps closest to the inner surface of the casing during the rotation of the carrier. When the door 14 is opened or removed from the casing the operator has free access to the carrier and the filled cartridges may be put into place, with the frangible portion or panel 19 adjacent to the wall of the casing. The cartridges may all be put into place without movement of the carrier or if desired in some cases the cartridges may all be inserted at about the same place with a step by step movement or rotation of the carrier, depending upon the size, form or location of the casing and the convenience afforded by the door or lid.

At the bottom of the casing is a delivery spout 27 preferably so designed as to provide for the delivery of the friction medium in the direction or condition most favorable for the particular use or the nature of the vehicle intended. As shown herein and as designed especially for an automobile, the delivery spout 27 has considerable length transversely of the path of the wheel and with the mouth portion somewhat restricted so as to cause the scattering or spreading of the sand S. The front side of the spout 65 extends downward beyond the level of the

rear side, whereby the outlet is guarded from mud or other extraneous matter that might tend to clog it. For convenience the term "sand" will be employed hereinafter with reference to the friction medium, but it will be understood that any other suitable medium such as salt, cinders, ashes, or the like, might be used.

Any suitable means may be provided, preferably under manual control of the driver or operator, for causing the movement of the cartridges so as to bring them successively or step by step into delivering position. To this end I show a pawl 28 mounted upon a pivot 29 connected to an actuating lever or arm 30 and oscillatable around the axis of the shaft 15, the arm having attached thereto a pull rod 31 or its equivalent whereby the driver of the machine has control of the carrier and cartridges. The pawl co-operates with a ratchet wheel 32 having as many teeth as there are pockets or spaces in the carrier. The normal position of the actuating means is indicated in Fig. 1 at which time one of the cartridges is located directly above the delivery spout. A spring 30' may co-operate with the arm 30 to return it to normal position.

Fixed upon the inner surface of the cylindrical wall of the casing 13 is an opener shown in the form of hooks 33. These are arranged at any convenient points in front of and above the delivery mouth. The point of each hook extends upward in position to receive the wire loop of the next cartridge during the step by step movement or rotation of the carrier as a result of the forward pull on the actuator rod 31. The throw of the rod corresponds to the length of a tooth of the ratchet wheel 32, and hence for each forward reciprocation of the actuator rod the carrier will be moved through a distance equal to the distance between centers of adjacent cartridges. Hence, the cartridge located adjacent to or next above the opener 33 will be carried downward and rearward past the opener. The action as indicated in Fig. 1 will cause the frangible panel 19 of such cartridge to be ruptured as a result of its wire being engaged by the hooks, and while the cartridge is carried onward toward its delivering position over the spout 27 the hooks will cause the complete rupture and withdrawal of the panel 19 and a clearing of the mouth 21, and thus the sand will be delivered directly and freely from this cartridge to the spout and thence will be scattered broadcast upon the track or road in front of the traction wheel. It must be borne in mind that in all sanding devices for traction vehicles the condition of the sand with respect to moisture and possible freezing is of paramount importance. Various at-

tempts have been made to keep the sand in perfectly fluid condition, including resistance coils or other heating means, all of which have either been too expensive or 5 have been otherwise objectionable and unsatisfactory. In my practice of this invention the cartridges are of such a nature as to be filled with sand in perfectly dry and fluid or mobile condition and after being so 10 filled the cartridges are hermetically sealed, thus insuring that the sand will be kept for an indefinite length of time free from moisture.

After the carrier is supplied with cartridges as above indicated the device is ready 15 for operation and in an emergency if the actuator rod 31 be reciprocated as described the cartridges may be emptied in succession through the delivery spout 27. Ordinarily 20 one or two of the cartridges will be sufficient to pass a dangerous spot, but if necessary all of the cartridges in the series may be emptied in rapid succession.

It will be noted that any empty cartridge 25 in the carrier will rise on the rear side of the supporting shaft so that any filled cartridges approaching the opening will assist in the actuation of the carrier. Undesired rotation, however, of the carrier will be prevented by reason of some suitable check, 30 such as a series of springs 24 secured upon the inner face of the door 14, and each having a notch 25 in which is normally engaged a rib 26 formed on the outer edge of 35 the cartridge. The cartridges are movable toward the free ends of the springs and hence they are easily slipped from the normal holding position indicated. At any 40 convenient time the empty shells may be withdrawn and fresh filled cartridges put in their places, and the empty shells may be either discarded or reused according to the material from which they are made. At any time the door 14 is opened the number 45 of wires found impaled on the hooks 33 will indicate the number of empty cartridges.

This invention insures reliability of operation of any traction vehicle to which it 50 may be applied, and furthermore it will be noted that with the device applied to a number of vehicles accustomed to traveling over the same road such as an icy slope, the surface of the roadway will soon be so coated with sand as to become safe and effective for general traffic. Furthermore 55 the construction is of a relatively simple mechanical nature and may be installed and kept in perfect operative condition at a cost insignificant in comparison with the practical value thereof.

I claim:

1. In a sanding device for traction wheels, a cartridge comprising an air and water tight receptacle carrying a supply of dry 65 sand, the cartridge being of a portable and

interchangeable nature and having formed along one side an opening for discharge of the sand, said opening being normally sealed hermetically by means of a frangible member, and means to rupture said frangible member to discharge the sand. 70

2. In a sanding device for a traction wheel, the combination of a support in front of the wheel, a carrier mounted upon the support, a plurality of sand carrying 75 cartridges mounted on the carrier and movable therewith with respect to the support, and means to cause the movement of the carrier and cartridges and the discharge of the contents thereof, substantially as set 80 forth.

3. A device as set forth in claim 2 in which the cartridges are hermetically sealed and each contains a supply of dry fluid sand. 85

4. A device as set forth in claim 2 in which the support is provided with a delivery passage and the means for moving the carrier tends to bring the cartridges in succession toward said passage and the successive opening of the cartridges for delivery of the contents thereof through the 90 passage.

5. In a sanding device, a self-contained package of sand, means to support and 95 move the package into discharging position, and a relatively fixed opening member past which the package is carried toward the delivery position and whereby the package is opened during such movement. 100

6. In a sanding device, the combination of an endless series of sand cartridge units, rotatable means to support and carry the units in succession into discharging position, each unit having a frangible portion, and opening means located along the path of movement of the several units and cooperating therewith for engagement with said frangible portion of the units to effect the immediate discharge of the contents 110 thereof.

7. A device as set forth in claim 6 in which the opening means comprises a sharp pointed hook upon which the frangible portions of the units are engaged during the 115 movement of the units.

8. A device as set forth in claim 5 in which the package is provided with a frangible closure including a looped member adapted for engagement over the fixed 120 opening member when the package is moved toward delivery position and whereby the package is opened.

9. A device as set forth in claim 2 in which the support includes a stationary 125 casing within which the carrier and cartridges are housed, and the casing includes a movable door to give access to the carrier.

10. A device as set forth in claim 2 in which the support includes a stationary cas- 130

ing having a front door through which the cartridges are projectable endwise toward the remote side of the casing, and check means is carried between the casing and the 5 cartridges to prevent premature movement of the carrier.

11. In a sanding device, the combination of a casing having a door and a rigid wall opposite the door, a carrier journaled 10 within the casing with its axis perpendicu-

lar to the door and said wall, a series of sand cartridges interchangeably inserted into said carrier parallel to the axis thereof, means acting between the casing and the cartridges to prevent rattling thereof, and 15 means to rotate the carrier to bring the cartridges into delivery position in succession.

In testimony whereof I affix my signature.

GUSTAV B. SCHOU.
